ROOM HEATER

George L. Moeller, St. Louis, Mo., assignor to
 Knapp-Monarch Company, St. Louis, Mo., a
 corporation of Missouri

Application February 17, 1942, Serial No. 431,202

7 Claims. (Cl. 219—39)

My present invention relates to a room heater of electric type having motor driven means for oscillating the heater to thereby sweep the room with a beam of heat.

One object of the invention is to provide a comparatively simple and inexpensive arrangement for oscillating a bowl-type heater by mounting the heater on an oscillatable motor, the motor being oscillated by self-operation.

A further object is to utilize the motor for drawing air across the heater and blowing air into the room, thus producing mechanical circulation thereof.

Still a further object is to utilize the reflector of the heater bowl as a means to reflect radiant heat therefrom and as a means to deflect radially blown air from a blower type fan, thereby causing it to travel in a general forward direction from the reflector.

Still another object is to provide a support for the heater which passes around the outside of the fan blades so as not to interfere with their operation.

With these and other objects in view, my invention consists in the construction, arrangement and combination of the various parts of my device whereby the objects contemplated are attained, as hereinafter more fully set forth, pointed out in my claims and illustrated in the accompanying drawing. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawing, in which:

Figure 1 is a side elevation of a room heater embodying my invention showing the reflector and heater in section;

Figure 2 is a sectional view as on the line 2—2 of Figure 1 showing only the motor, the heater, the fan and a section of the reflector;

Figure 3 is a front elevation of the heater; and

Figure 4 is a rear elevation thereof on an enlarged scale as taken on the line 4—4 of Figure 1 to show a portion of the support for the heater.

On the accompanying drawing I have used the reference numeral 10 to indicate a base. Tiltably mounted on the base 10 is a yoke 12 having an upstanding sleeve 13. A clamp screw 14 is provided for clamping the yoke 12 with relation to the base 10.

An electric motor 16 is provided with a down-

wardly extending stud 17 rotatable in the sleeve 13, a screw 18 being provided for cooperation with a groove 19 in the stud 17 to prevent removal of the motor from the base.

The motor 16 has a shaft 20 rotated in the usual manner by energization of the motor. The motor 16 is oscillatable relative to the base 10, as is usual in connection with oscillating fans, as by a shaft 21 geared down with relation to the motor shaft 20 and carrying a crank arm 22. The crank arm 22 is connected by a link 23 with a lateral arm 24 on the sleeve 13.

A bowl-like reflector 25 is supported on the motor 16 as by bolts 26, and is accordingly oscillatable with the motor. Within the reflector a bracket B supports a heater H. The bracket B has a central portion 27, shown in Figure 4, and four arms 28. The arms 28 are bent rearwardly as at 29, and their ends are connected by screws 30 to the reflector 25.

The heater H comprises a cone-shaped support 31 of insulation having a groove therearound in which a coiled resistance element 32 is wound, the ends of the element 32, indicated at 33 and 34, connecting with clips 35 secured to terminal bolts 36. The terminal bolts 36 pass through an embossed portion 37 of the bracket B and are suitably insulated therefrom by the usual mica washers. Terminal clips 38 are mounted on the rear ends of the screws 36 and are connected with wires 39. The wires 39 pass through porcelain insulating sleeves 40, 41 and 42 into the housing of the motor 16, where they are connected with supply wires 43 also extending into the housing. The supply wires 43 have a plug for connection to a service outlet on their outer end, in the usual manner, and are connected to the motor 16 as well as to the heater supply wires 39.

The bracket B, it will be noted, supports the heater H, spaced forwardly from the reflector 25 in the proper position for radiant heat to be reflected from the heater by the reflector toward the front of the reflector. At the same time, the construction of the bracket B is such that it provides a space in which a fan 44 may rotate. The fan 44 is of the blower type, and, accordingly, draws air in at the center and discharges it radially. It therefore circulates air in the path indicated by the arrows a, b, c and d. The air is drawn in, as indicated by the arrow a, across the heating element 32 to pick up heat therefrom, and then passes into the center of the fan blades 44, as indicated by arrow b. Rotation of the fan blades causes the air to be blown radially outward, as at c, and the air is then deflected by the

reflector 25, as indicated by the arrow *d*. Thus, the reflector acts also as a deflector for the air, in addition to reflecting radiant heat from the heater *H*.

To protect objects in front of the heater from getting too close to it, and also to protect the floor in case the heater is tipped over forwardly, a wire guard 45 is provided in the form of radial wires, connected at their center by a plate 46 and having their terminal ends secured to an annular wire 47. The annular wire 47 is received in a groove 48 at the periphery of the reflector 25.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a room heater, a base, a motor swingably mounted thereon, means operable from said motor for imparting an oscillating movement to said motor relative to said base, a bowl-like reflector supported on said motor for oscillation therewith, an electric heater supported in position in said reflector for heat from said heater to be reflected by the reflector, said motor having a shaft projecting into said reflector, and a fan on said shaft to draw air into said reflector and over said heater and project the air heated thereby toward the reflector whereby it is deflected by, and then travels forwardly from said reflector.

2. In a room heater, a base, a reflector and a motor mounted thereon, a heater supported in position in said reflector for heat from said heater to be reflected by the reflector, said motor having a shaft projecting into said reflector, a fan on said shaft and rotating relative to said reflector for drawing air over said heater and projecting the air heated thereby radially from the fan blades toward said reflector, said reflector deflecting the air from a radial direction and projecting it forwardly from said reflector.

3. In a heater of the character disclosed, a base, a motor oscillatably mounted thereon, a combined heat reflector and air deflector supported on said motor for oscillation therewith, an electric heater positioned with respect to said reflector for heat from the heater to be reflected thereby, and a centrifugal fan operated by said motor and positioned in said deflector for air

taken in adjacent the center of the deflector to be thrown peripherally outward and deflected forwardly by the deflector.

4. In a room heater, a base, a motor mounted thereon, a bowl-like reflector, a cone-shaped electric heater supported therein for reflection of heat from said heater by the reflector, said motor having a shaft projecting into said reflector, and a centrifugal fan on said shaft between said heater and said reflector.

5. In a room heater, a base, a motor oscillatably mounted thereon, said motor having a shaft, means operable from said shaft to impart movement to said motor and to oscillate it relative to said base, a bowl-like reflector supported on said motor for oscillation therewith, a cone-shaped electric heater supported in position in said reflector for heat from the heater to be reflected by the reflector, said motor shaft projecting into said reflector, a centrifugal blower type fan on said shaft immediately behind said cone-shaped heater, supporting brackets for said heater extending around said fan and connected with said reflector at the back thereof, said fan drawing air over said cone-shaped heater and expelling it radially into said reflector, said reflector acting as a deflector for the air to deflect it forwardly from said reflector.

6. In a room heater, a base, a motor oscillatably mounted thereon, said motor having a shaft, means operable from said shaft to impart movement to said motor and to oscillate it relative to said base, a reflector supported on said motor for oscillation therewith, a heater, said motor shaft projecting into said reflector, a centrifugal blower type fan on said shaft immediately behind said heater, supporting brackets for said heater extending around said fan and connected with said reflector behind the fan, said fan drawing air over said heater and expelling it radially into said reflector.

7. In a room heater, a motor having a shaft, a bowl-like reflector supported thereon, a heater supported in front of said reflector, a centrifugal blower type fan on said shaft between said heater and said reflector, open supporting brackets for said heater extending around said fan and connected with said reflector at the back of the fan, said fan rotating independent of said reflector and drawing air over said heater and expelling it radially and directly through said open supporting brackets into said reflector whereby said reflector deflects the air forwardly.

GEORGE L. MOELLER.
